UNITED STATES PATENT OFFICE.

DAVID PETRI-PALMEDO, OF BRIDGEPORT, CONNECTICUT, ASSIGNOR TO MUFFLER PHONE MFG. CO., INC., OF MERIDEN, CONNECTICUT, A CORPORATION.

MUFFLER ATTACHMENT FOR TELEPHONES.

1,372,162.

Specification of Letters Patent. Patented Mar. 22, 1921.

Application filed May 27, 1920. Serial No. 384,703.

To all whom it may concern:

Be it known that I, DAVID PETRI-PALMEDO, a citizen of the United States, residing at Bridgeport, in the county of Fairfield 5 and State of Connecticut, have invented a new and useful Improvement in Muffler Attachments for Telephones; and I do hereby declare the following, when taken in connection with the accompanying drawings 10 and the characters of reference marked thereon, to be a full, clear, and exact description of the same, and which said drawings constitute part of this application, and represent, in—

15 Figure 1, a face view of a muffler attachment for telephones, constructed in accordance with my invention.

Fig. 2, a side view of the same shown as attached to a telephone.

20 Fig. 3, a front view of the rear plate and diaphragm.

Fig. 4, a vertical sectional view of the muffler attachment.

Fig. 5, a face view of the rear plate detached.

Fig. 6, a rear view of the front plate detached.

Fig. 7, a face view of the diaphragm detached.

30 Fig. 8, a face view of one of the linings detached.

Fig. 9, a side view, partly in section, of a modified form of my invention.

Fig. 10, a sectional view on the line 10—10 35 of Fig. 9.

This invention relates to an improvement in muffler attachments for telephones, the object being to permit the use of a telephone in the presence of others without being 40 overheard and furthermore to so increase the sound for the transmitter that usual speaking tones may be readily heard; and the invention consists in the construction and arrangement of parts as hereinafter described and particularly recited in the 45 claims.

In one form of my invention, this device takes the place of the ordinary conical transmitter of a telephone instrument and 50 consists of a transmitter 15 having a screw threaded stem 16 for connection with the usual telephone instrument 17. This transmitter is formed integral with a plate-like member 18 which is formed on its inner face 55 with a series of outwardly projecting studs

19 having reduced ends 20 to enter sockets 21 formed in a front plate 22 corresponding in diameter to the plate 18 and separated therefrom by the studs. The outer plate 18 is formed with a collar 23 to which a mouth-piece 24 is connected, this mouth-piece being so formed that it will inclose the lips of the person speaking, yet leave them perfectly free to move.

Arranged centrally between the plates is 65 a diaphragm 25 of felt, having clearance holes for the studs 19 by which it is held in place, and formed with a central opening 26 for the insertion of the inner end of a rear deflector 27, to the outer end of which is 70 fixed a front deflector 28, these two deflectors forming a direct channel from the mouth-piece to the telephone. The diaphragm 25 is held in position by inwardly projecting lugs 29 and 30 formed in the 75 adjacent faces of the plates. The diameter of the diaphragm is less than the diameter of the plates, which are formed near their outer edges with annular channels 31 and 32. Against the inner face of the outer plate is 80 a lining 33 and against the forward face of the inner plate is a corresponding lining 34 held in place by the studs 19 and lugs 29 and 30.

The space around the deflector opens into 85 a space between the diaphragm and the lining, forming a contracted passage to the channels 31 and 32 and to the space left between the adjacent edges of the plates. With this construction, the sound-waves 90 have a straight passage to the diaphragm of the transmitter. In speaking into a closed receptacle, considerable air pressure is created and this is relieved by the passage around the deflector and outward between 95 the plates, this passage being loosely sealed by the edges of the felt diaphragm and linings so as to break the sound-waves but permit the escape of air.

While it is generally desirable to form 100 the rear plate with the conical transmitter for attachment to the telephone, it is sometimes desired to apply a muffler attached to the mouth-piece of a telephone, as shown in Figs. 9 and 10, and for this purpose, I form 105 the back plate with an annular collar 35 in place of the conical transmitter 15 and in the bottom of the collar is an annular groove 36 in which a packing-ring 37 is placed to receive the edge of an ordinary mouth-piece 110

38 to which it is attached by placing balls 39 around the outside of the mouth-piece, the balls being held by a cap 40 locked with the collar 35 by a spring-ring 41 located in 5 grooves formed in the adjacent faces of the ring and sleeve, the cap having an inwardly projecting flange 42 formed with cam surfaces 43 by which the balls are crowded against the edge of the mouth-piece.

10 I claim:

1. A muffler attachment for telephones, comprising two plates one adapted to be connected with a telephone and the other provided with a mouth-piece, a diaphragm 15 located between said plates, a two-part deflector mounted in said diaphragm and forming a direct opening, and linings applied to the adjacent faces of the plates.

2. A muffler attachment for telephones, 20 comprising a back plate and a front plate connected together so as to leave a space between them, a diaphragm located between said plates, a two-part deflector mounted in the center of said diaphragm, and linings 25 applied to the inner faces of the plates and

forming passages between the plates and diaphragm for the escape of air between the outer edges of the plates.

3. A muffler attachment for telephones, comprising two plates one adapted to be 30 connected with a telephone and the other provided with a mouth-piece, one plate formed with studs adapted to engage with the other plate whereby the plates are spaced apart, said plates formed near their 35 outer edges with annular channels, a diaphragm located centrally between the plates, a two-part deflector mounted in the center of said diaphragm and forming a direct opening through the muffler, and linings applied to the inner faces of the said plates and forming air passages between the plates to the outer edges thereof.

In testimony whereof, I have signed this specification in the presence of two subscribers. 45

DAVID PETRI-PALMEDO.
